G. F. BORN.
WINDOW SCREEN.
APPLICATION FILED JUNE 11, 1913.

Patented Sept. 8, 1914.

UNITED STATES PATENT OFFICE.

GABRIEL F. BORN, OF GNADENHUTTEN, OHIO.

WINDOW-SCREEN.

1,110,036.

Specification of Letters Patent.

Patented Sept. 8, 1914.

Application filed June 11, 1913. Serial No. 773,112.

To all whom it may concern:

Be it known that I, GABRIEL F. BORN, a citizen of the United States, residing at Gnadenhutten, in the county of Tuscarawas, State of Ohio, have invented certain new and useful Improvements in Window-Screens; and I do hereby declare the following to be a full, clear, and exact description of the invention, such as will enable others skilled in the art to which it appertains to make and use the same.

This invention relates to window screens, and particularly that class wherein a rolling screen is employed and arranged to be actuated by the sash to close the opening when the lower sash is raised or the upper sash lowered.

The object of the invention resides in the provision in a screen of the class described of means whereby the said screen may be applied to windows of varying widths.

In carrying out the preferred form of this invention, there is preferably employed the form of screen shown in my previous patent #1,055,381, issued March 14--1913.

With the above and other objects and advantages in view, the invention resides in the novel combination, formation and arrangement of parts to be more fully herein-after described and illustrated in the accompanying drawings and particularly pointed out in the claims hereto appended.

Reference is had to the accompanying drawings wherein similar characters of reference designate corresponding parts throughout the several views, and in which: Figure 1 is an elevational view of the outside of a window of relatively great width with the improved device associated therewith; Fig. 2 is a vertical longitudinal sectional view therethrough, Fig. 3 is a transverse sectional view taken on the line 3--3 of Fig. 1, and Fig. 4 is a perspective view of the plate and the rod carried thereby.

The device may be applied to either the upper or lower portion of the window, or both portions as may be desired, without necessitating any material changes or modifications. It is therefore evident that in order to make a sufficient disclosure of the invention it is only necessary to describe the device as applied to one portion of the window. In the following description and in the drawings the device is shown as applied to the lower portion of the window.

Referring now more particularly to the

drawings, 5 designates the curved longitudinally extending portion of the screen casing having at its inner top edge, the upward extension 6 forming a part of my aforementioned previous patent. In the present invention this casing is of a standard length and provided with end portions 7 in which are journaled the pintles of the screen carrying spring roller 8. These end pieces are extended inwardly past the casing 5 for a purpose to be hereinafter made apparent. The screen 9 is wound on the roller 8 and secured to a member 10 extending outwardly from the bottom rail 11 of the lower window sash. This member 10 also carries the angular plate 12 of my previous patent, fitting over the upward extension 6 of the casing to protect the screen and roller from the elements when the sash is in its lowermost position.

It is observed that the member 10 carried by the sash is of a length equal to the length of the casing 5 and has its outer terminating short of the sides of the relatively wide sash illustrated. It is thus observed that when the sash is raised there is considerable space between the sides of the screen and the sides of the window frame.

As heretofore stated the primary object of the invention resides in the provision of means for covering this space, which varies according to the width of the window. To accomplish this a plate 13 is provided which is angular at each side of the window frame. This plate is angular in cross section and has one of its sides secured as at 14 to the side of the window frame outwardly of the sash. The other side of the plate extends inwardly in substantially parallel relation to the sash and is disposed in a plane outwardly of and adjacent the outer sash holding strip 16. The lower end of this side of the strip is provided with a cutaway portion 17 which engages over the top of the casing 5 of the end portion 7 of the casing 5.

Carried by the free side of each plate 13 is a vertically extending bar 18 which is adjustably secured to the plate by means of screws or bolts 19 passed through transverse slots 20 formed in the said side of the plate and engaging the bar, which is preferably rectangular in cross section and which has its side faces lying in the planes of the side faces of the sash holding strip 16. The lower end of this rod is provided with a cutaway portion which receives the exten-

sion of the end 7 of the casing 5, the said bar being disposed directly inwardly of the said end. The inner edge of the bar adjacent the plate 13 is provided with a longitudinally extending cutaway portion 21, the walls of which in conjunction with the edge of the plate 13 define a groove which is adapted to receive the side edge of the screen and the plate 12 for sliding movement 10 therein.

It is observed that the cutaway portion 17 of the plate may have its side edge spaced from the end 7 of the roller casing. To provide an adjustable closure for this space a 15 plate 22 is provided having a transverse slot 23, a bolt 24 passing through the plate 13 and the slot in the plate 22 to clamp the plates in relation. The plate 22 is held against pivotal movement on the bolt 24 by 20 having its inner side edge in engagement with the end 7 of the casing.

From the foregoing it will be observed that a structure has been provided which will permit the rolling screen described in 25 my previous patent to be applied to windows of varying widths.

It will be understood that various minor changes and modifications within the scope of the appended claims may be made without in any manner departing from the spirit 30 of the invention.

What is claimed is:

1. The combination with a window frame, 35 of a sash mounted therein, a housing secured to a transverse member of the frame, screen

material extending from the housing to the sash, the ends of the housing being extended inwardly, a plate secured to each side of the frame and extended inwardly and provided with a cutaway portion for receiving the extended ends of the housing, a bar carried by the inner edge of the plate and laterally adjustable with relation thereto, the said bar being provided on one face with a cutaway portion forming with the edge of the plate a vertical recess for slidably receiving the edge of the screen, the said bar being cut away at its lower end to receive the extended end of the housing, and a plate carried by the lower end of the first-mentioned plate and adjustable laterally to engage the outer face of the extended end of the housing. 40 45 50

2. The combination with a window frame, of a sash mounted therein, a housing secured to a transverse member of the frame, screen 55 material extending from the housing to the sash, the ends of the housing being extended inwardly, a plate secured to each side of the frame and extended inwardly and provided with a cutaway portion for receiving the extended ends of the housing and a plate carried by the first-mentioned plate and adjustable laterally to engage the outer face of the end of the housing. 60 65

In testimony whereof, I affix my signature, in the presence of two witnesses.

GABRIEL F. BORN.
